(57) **CLAIM**

The ornamental design for a vehicle tire, as shown and described.

DESCRIPTION

1. Vehicle tire

1.1 is an enlarged partial front view of the vehicle tire showing my new design;

1.2 is a front perspective view thereof;

1.3 is a left side elevation view thereof;

1.4 is a right side elevation view thereof;

1.5 is a front elevation view thereof; and

1.6 is a top elevation view thereof.

The dashed-dot broken lines in figure 1.5 is a demarcation of the portion of the design visible in the enlarged partial front view of 1.1 and forms no part of the claimed design.
